Primary Examiner — Clare E Heflin(74) *Attorney, Agent, or Firm* — Tarter Krinsky & Drogin LLP(57) **CLAIM**

I claim the ornamental design for a solar wall light, as shown and described.

DESCRIPTION

FIG. 1 is a front perspective view of a solar wall light showing my new design

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines shown on the drawings represent portions of the solar wall light that form no part of the claimed design.
